United States Patent Office

Des. 189,206
Patented Nov. 8, 1960

189,206

SOCK OR SIMILAR ARTICLE

Geraldine B. Thompson, 2131 W. 103rd Place,
Los Angeles, Calif.

Filed Oct. 5, 1959, Ser. No. 57,820

Term of patent 14 years

(Cl. D47—7)

I claim:

The ornamental design for a sock or similar article, substantially as shown.
